UNITED STATES PATENT OFFICE.

CYRUS HOWARD HAPGOOD, OF NUTLEY, NEW JERSEY, ASSIGNOR TO THE DE LAVAL SEPARATOR COMPANY, OF NEW YORK, N. Y., A CORPORATION OF NEW JERSEY.

VACUUM PUMP.

Application filed November 30, 1926. Serial No. 151,659.

A highly efficient type of vacuum pump comprises a housing, a hollow rotor within and eccentric to the housing, an air inlet port to, and an air outlet port from, the air space between housing and rotor, 5 slideable vanes carried by the rotor and arranged radially to the rotor shaft and which extend into said air space and contact with the housing during the rotation of the rotor, oil reservoirs open to the atmosphere within the end heads of the housing and adapted to receive drips from the bearings and which are freely open to the interior of the rotor so as to allow oil to freely flow thereinto and 10 maintain a sealing body of oil therein, an oil separator in the air discharge passage, and oil passages from the oil separator to the bearings and to the interior of the rotor. Such a vacuum pump is shown in the Leitch 15 Patent No. 1,367,554, dated February 8, 1921, and the Hall Patent No. 1,374,650, dated April 12, 1921.

In the operation of such a pump, conditions arise which cause oil to escape from the 20 pump around the bearings, thereby causing waste. Among such causes are variations from the normal air pressure conditions within the pump. For example, in the normal operation of the pump, when used as a part 25 of a milking machine outfit, the absolute pressure at the inlet port to the air compression space between housing and rotor may be fifteen inches mercury, while at the outlet port from this space the pressure is close to 30 atmospheric. If any condition should arise that increases the absolute pressure at the inlet, as, for instance, if the teat cups drop off the cow and the absolute pressure at the inlet consequently jumps to atmospheric 35 pressure, the pressure at the outlet port of the housing will rise to two atmospheres. This pressure forces air between the ends of the rotor and the adjacent housing caps into the interior of the rotor, whence it freely escapes into the oil reservoirs, causing oil to 40 be blown over the edge of the bearing surrounding the chamber in the end head of the housing.

The oil losses arising during normal operation and from abnormal, but recurring, operative conditions have been assumed to be due to back pressure at the discharge of the pump operating through oil passages communicating with the interior of the rotor: and, for 45 the purpose of avoiding the supposed effects

of such back pressure, such passages have been restricted to the greatest possible degree; with the result, however, of accentuating, instead of remedying, the objectionable conditions. My invention had its inception 50 in the discovery of the actual phenomena that occur during abnormal working conditions like the illustrative case cited, which resulted in the provision of means whereby communication between the interior of the 55 rotor and the oil reservoir is relatively restricted while communication between the interior of the rotor and the discharge from the pump to atmosphere is relatively free. The former provision limits the inflow of compressed air from the interior of the rotor to the oil reservoirs, while by means of the latter provision, the interior of the rotor communicates with the atmosphere so freely that no opportunity for building up substantial 60 air pressure in the reservoirs or the interior 65 of the rotor is afforded. By reconstructing and simplifying the bearings, it has been found possible to reduce the diameter of the end axial opening in the housing and thereby 70 raise the lower edge of this opening further above the oil level in the reservoirs, thereby 75 still further reducing the likelihood of escape of oil at this point.

A preferred embodiment of the invention 80 is shown in the drawings, in which—

Fig. 1 is a longitudinal sectional view of the pump.

Fig. 2 is a cross-section through the pump 85 on the line 2—2 of Fig. 1.

Fig. 3 is a cross-section through the pump 90 on the line 3—3 of Fig. 1.

Rotor *a* is mounted on a shaft *b* carried by bearings *c*, *c'* on the end heads *d* and *e* of housing *f*. Between the shell of the rotor and the 95 wall of the housing is the air compression space. Rotor *a* has slots through which wings or vanes *g* extend into contact with the inner wall of the housing, these vanes sliding toward and from the shaft in the rotation of the 100 rotor, which is eccentrically disposed with relation to the housing. *h* is the inlet port to the air compression space between rotor and housing and *i* the outlet port from said space. The outlet port *i* communicates with a passage 105 leading through an oil separator (not shown in detail) to the discharge *j* from the housing. Instead of providing separate reservoirs in the two housing heads *d* and *e* between which the oil overflows through large openings in 110

end heads that communicate with the interior of the rotor, the reservoirs are connected by a passage extending through the lower part of the housing; or, in other words, the housing is (preferably) so shaped as to afford a single reservoir *k*, which extends through the lower part of the housing and into both end heads. Instead of providing large openings between the reservoir and the interior of the rotor, 10 one or more restricted openings are provided. Preferably a single restricted opening *m* is formed in one of the end heads of the housing. Instead of restricting the flow of air between the discharge *j* and the interior of the 15 rotor, the clearances are made so large as to form relatively unrestricted passages *n* so as to insure the maintenance, under all conditions, of pressure inside the rotor corresponding to that at the discharge *j*.

20 The end head *d* of the housing is provided with an opening concentric to the axis, through which opening projects the hub of a pulley *o*, affording an annular space between the housing and the pulley hub. The lower 25 edge of this annular space is a substantial distance above the normal oil level within the housing. This factor, however, is of minor importance in preventing oil leakage. The major factors are the provision of a relatively 30 unrestricted passage between the interior of the rotor and the air discharge *j* from the housing, and, secondarily, the provision of a relatively restricted opening between the interior of the rotor and the oil reservoir *k*.

35 Owing to the free outflow of air at the discharge *j*, no substantial pressure can build up therein notwithstanding the building up of pressure in the air compression space of the pump. While air pressure tends to build up 40 in the interior of the rotor, such pressure is capable of being relieved through both opening *m* and passages *n*. The unrestricted character of the passages *n* permits free outflow of air from the interior of the rotor and prevents any substantial pressure being built up 45 therein and consequently there can be no substantial inflow of compressed air into the reservoir. Therefore, the air pressure in the reservoir can never rise substantially above normal 50 atmospheric pressure and hence no conditions can exist which tends to cause oil leakage from the reservoir.

The gear casings outside the housing freely communicate through opening *r* with the atmosphere and through passage *p* with the reservoir *k*.

To automatically supply the reservoir with oil and maintain the level of oil therein, I provide a perforated cup *t* extending into the 55 oil reservoir space within the housing. Extending through the bottom of the cup is an oil discharge tube *u* and an air admission tube *v*. Oil tube *u* is relatively short, but extends

into the oil reservoir below the lower end of tube *v*. Tube *v* extends a substantial distance 60 into, or through, cup *t*. A bottle containing oil is adapted to be inverted and inserted into the cup. A ring *w* may be positioned around the mouth of the cup to afford a support for a bottle protector casing (not shown).

In operation, the level of oil in the reservoir cannot fall substantially below the lower end of tube *v*, because as soon as that occurs to a slight extent, air escapes from the reservoir through pipe *v* into the air space in the bottle above the oil, and the air pressure therein immediately acts to expel oil from the bottle through pipe *u* and raise the level of oil in the reservoir until the outlet from pipe *v* is closed and the air pressure in the reservoir balances 75 the air pressure above the oil body and the hydrostatic pressure of the column of oil in the bottle.

Having now fully described my invention, what I claim and desire to protect by Letters 80 Patent is:

1. In a vacuum pump, the combination with a housing, a hollow rotor eccentrically disposed therein, slideable vanes extending into the hollow interior of the rotor and into the air space between rotor and housing, an oil reservoir in the housing, the housing being provided with an inlet and an outlet to said air space, and a discharge to atmosphere communicating with said outlet, of means providing a relatively unrestricted passage for air between the hollow interior of the rotor and said discharge, there being an opening between the oil reservoir and the hollow interior of the rotor allowing flow of oil from reservoir to rotor, said opening being relatively restricted to limit the flow of air therethrough relative to the flow of air between the hollow interior of the rotor and the discharge.

2. In a vacuum pump, the combination with a housing, a hollow rotor eccentrically disposed therein, slideable vanes extending into the hollow interior of the rotor and into the air space between rotor and housing, the housing having an oil reservoir extending beneath the rotor and on opposite sides thereof, the housing having also an inlet and an outlet to said air space and a discharge to atmosphere communicating with said outlet, of means providing a relatively unrestricted air passage between the hollow interior of the rotor and said discharge, there being an opening in one of the end heads of the housing affording a relatively restricted opening for oil and air flow between the reservoir and the hollow interior of the rotor.

In testimony of which invention, I have hereunto set my hand, at city of New York, on this 12th day of November, 1926.

CYRUS HOWARD HAPGOOD.
